APPARATUS FOR TREATING STRANDS

Vincent A. Rayburn, Baltimore, Md., assignor to
 Western Electric Company, Incorporated, New
 York, N. Y., a corporation of New York

Application September 7, 1940, Serial No. 355,879

9 Claims. (Cl. 91—53)

This invention relates to apparatus for treating a strand and more particularly to an apparatus for smoothing or polishing weatherproofed conductors.

In applying weatherproofing material to a rubber and textile covered wire the application of these materials does not always leave the resulting product in a uniform and smooth condition, and therefore it is desirable to smooth or polish the conductor after the application of the weatherproofing materials.

An object of the present invention is to provide an effective and efficient apparatus for smoothing or polishing conductors or the like.

In accordance with one embodiment of the invention, an apparatus is provided in which a plurality of wiping dies is displaced angularly about the conductor and spaced longitudinally along the conductor to smooth the surface of a conductor under water.

A complete understanding of the invention may be had by reference to the following description taken in conjunction with the accompanying drawing, in which

Fig. 1 is a side elevation partly in section of an apparatus embodying the invention;

Fig. 2 is a fragmentary plan view of the apparatus;

Fig. 3 is a sectional view taken on line 3—3 of Fig. 1;

Fig. 4 is a detail view of one of the upper die elements;

Fig. 5 is a detail view of one of the lower die elements; and

Fig. 6 is another detail view of the die element shown in Fig. 5.

The invention will be described in connection with the weatherproofing of a rubber and textile covered conductor, although only the polishing or wiping apparatus is disclosed herein.

In weatherproofing a rubber and textile covered conductor, the conductor is in some cases first passed through a bath of an asphalt saturant to saturate the textile material. The conductor is then passed through a bath of stearin pitch and the excess material is removed. Thereafter the conductor is usually passed through a quantity of powdered talc, mica, or other similar material, to reduce the stickiness of the surface. From this treatment the conductor is passed into the smoothing or polishing apparatus disclosed herein.

This apparatus may comprise a tank 7 having a shelf 8 upon which the smoothing apparatus is mounted. Underneath the shelf 8 is a distribut-

ing chamber 9 having an inlet pipe 11 through which water is admitted to the chamber and from the chamber the water passes through a plurality of apertures 12 in the shelf 8. The polishing apparatus comprises a base 13 having apertures which coincide with the apertures 12 in the shelf 8. At the ends of base 13 are end walls 14 and 15 having slots therein for the passage of conductors and forming in effect weirs, the water flowing continuously through the slots in the end walls into the tank 7, from which it may drain through an overflow pipe 16. Mounted upon the base 13, and preferably integral therewith, are a plurality of die holders 17, preferably of an even number and shown in the drawing as four in number. The lower die holders have dies 18 and 19 mounted therein held in place by set screws. One of the lower dies 19 is shown in Fig. 5. These dies are provided with slots 21 of such a size as to engage the wire on three sides, and one lip 22 of a die is made longer than the other so as to hold the conductor more securely therein when the dies are angularly mounted in the die holders.

The dies are similarly shaped at both ends so that when one end becomes worn the other end may be used. Each of the dies is provided with a sloping leading end 23 so that when a knot or splice reaches the die the knot or splice will ride up on the sloping surface, moving the conductor out of the slot so as to allow the knot or splice to pass without tearing the wire. The dies 18 and 19 are identical except that one is an inverted image of the other. The reason for this is that the dies are mounted as shown in Fig. 3 angularly displaced 120° from each other. This will cause the longer lip 22 of each die to lie adjacent the lower side of the conductor to prevent the conductor from being forced completely out of the die when a knot or splice passes.

As stated above, the lower dies 18 and 19 are longitudinally displaced along the length of the conductor, and between a set of stationary dies 18 and 19 a movable die 31 is disposed which is also at an angle of 120° to each of the dies 18 and 19. The die 31 is also provided with a slot 32, but the lips of this die are differently shaped than the lips of the dies 18 and 19, because this die is intended to exert a downward pressure on the conductors. The dies 31 are held in die holders 33 carried by bell crank arms 34 which are pivotally mounted on a bar 35 by stub shafts 36. The bar 35 is provided with a plurality of eyelets 37 to which a spring 38 is attached, the opposite end of the spring being attached to one

arm of the bell crank lever 34 to continuously urge the upper dies 31 against the conductor, causing the conductor to move in a slightly tortuous path. One end of bar 35 is bifurcated, as shown at 41, to engage a pin 42 in the end wall 14, thereby pivotally and removably mounting the bar on the pin 42. The opposite end of bar 35 is provided with an enlargement 44 which engages against the inner side of end wall 15, whereby the bar is held against longitudinal movement while in operative position. The latter end of the bar may also be provided with a handle 45 projecting through a slot in the end wall for lifting the upper dies away from the conductor for threading a conductor into the machine. The dies are preferably made of cast iron containing approximately 3% of nickel. It has been found that when these dies are made of steel they tend to become gummed and clogged. By making the dies of cast iron this defect is eliminated and the small amount of nickel is added to the cast iron to increase the hardness and wearing properties of the die.

In operation of the apparatus the wire coming from the talc or mica applicator is still warm, since the asphalt and stearin pitch are applied in a heated condition. By passing the weather-proof conductor into the water bath and immediately wiping and smoothing the surface, an effective polish is applied thereto, working the talc or other coating material into the surface of the conductor, and at the same time the water prevents the dies from becoming fouled and clogged.

It will be understood that the nature and embodiment of the invention herein described are merely illustrative and that many changes and modifications may be made therein without departing from the spirit and scope of the invention.

What is claimed is:

1. An apparatus for treating a strand comprising a plurality of dies each adapted to partially surround a strand, said dies being angularly and longitudinally disposed with respect to each other to collectively surround the strand, and means for advancing a strand through said dies.

2. An apparatus for treating strand material comprising a pair of stationary dies angularly disposed relative to each other and longitudinally displaced, a movable die angularly disposed with respect to said first mentioned dies and located longitudinally therebetween for urging a strand against said dies, and means for advancing a strand through said dies.

3. An apparatus for treating a strand comprising a plurality of grooved dies angularly and

longitudinally spaced around and along the path of a strand to collectively surround the strand, means operating on one of said dies for yieldingly engaging a strand in said grooves, and means for advancing a strand through said grooves.

4. An apparatus for treating strand material comprising a pair of stationary dies displaced substantially 120° around the path of a conductor, and spaced longitudinally of said path, a movable third die spaced substantially 120° from said first mentioned dies and longitudinally located between said dies, means for yieldingly urging said movable die toward said path to engage a strand between said dies, and means for advancing a strand through said dies.

5. An apparatus for treating strand material comprising a pair of lower dies having grooves formed between two lips, the lower lip of said dies being longer than the upper lip, a third die located above said dies having a groove, and means for yieldingly urging said third die toward a strand to engage the strand with the lower dies.

6. An apparatus for treating strand material coated with asphaltic material comprising a tank, a pair of dies angularly mounted on the base of said tank, a third die for urging a strand against said first mentioned dies, and means for submerging said strand in water during the treating operation.

7. An apparatus for treating strand material, comprising a plurality of dies angularly and longitudinally disposed with respect to each other to collectively surround a strand, means for advancing said strand through the dies, and means for urging the dies relatively toward the path of the strand.

8. An apparatus for treating strand material, comprising a pair of dies longitudinally disposed with respect to each other and each having a slot therein for engaging a strand on approximately half of its circumference, said dies each having a sloping, leading face for directing a strand having an enlargement out of the slot, and another similar die urged toward the path of the strand to operate on the strand at a point between said dies.

9. An apparatus for treating strand material, comprising a series of alternate stationary and movable dies, said dies being angularly and longitudinally disposed with respect to each other, whereby the movable dies urge a strand passing between the series of dies into contact with the stationary dies.

VINCENT A. RAYBURN.
